[57] CLAIM

The ornamental design for a floor clock, substantially as shown.

DESCRIPTION

FIG. 1 is a right front perspective view of a floor clock showing my new design;

FIG. 2 is a right side elevational view thereof, the left

side being a mirror image thereto;

FIG. 3 is a top plan view thereof.

The rear of the clock, now shown, is flat, plain, and unornamented.

Fig. 2.

Fig. 3.
